RAIL CLAMP POSITION INDICATOR

Alfred Teplitz, Pittsburgh, Pa., assignor to United States Steel Corporation, a corporation of New Jersey

Application February 21, 1957, Serial No. 641,614

2 Claims. (Cl. 200—153)

The present invention relates generally to rail-clamping mechanisms and has for its primary object the provision of a safety signal device utilized in combination with a rail-clamping mechanism to indicate whether the mechanism is in clamping engagement with a running rail.

It is a further object of the invention to provide a rail-clamp position indicator which is simple and rugged in construction and not subject to damage by weather or environmental conditions and is, therefore, especially suitable for use on exposed structures such as ore bridges and the like.

These and other objects will become more apparent after referring to the following specification and attached drawings in which:

Figure 1 is an elevational view of the rail clamping mechanism of an ore bridge having the device of the invention installed thereon;

Figure 2 is an enlarged front elevational view of the device of the invention;

Figure 3 is an end view of the device of the invention taken on the line III—III of Figure 2;

Figure 4 is a sectional view taken on the line IV—IV of Figure 2;

Figure 5 is a sectional view taken on the line V—V of Figure 2 enlarged to show detail; and

Figure 6 is a plan view of Figure 5.

A preferred embodiment of the invention will now be described in conjunction with a rail-clamp mechanism of the type disclosed by Kersting Patent No. 1,988,173.

Referring more particularly to the drawings reference numeral 2 designates generally the device of the invention installed on a clamp arm 4 of a rail-clamping mechanism 6, such as is shown in Patent No. 1,988,173, of an ore bridge. The rail-clamping mechanism 6 is shown somewhat diagrammatically in Figure 1, and includes a pair of opposed, generally vertical clamp arms 4 and 4' pivoted at their lower ends by means of spaced plates 8 and pins 10. A linkage 12 connects the upper portion of the clamp arms 4 and 4' with spring means 14 which constantly urges the lower end of the clamp arms into clamping engagement with the head of a running rail R. Release of the clamp arms is effected by means of pulleys 16 and cable 18. The structure and functioning of clamping mechanism 6 is fully described in the Kersting patent referred to above and, therefore, will not be more fully described herein.

The device of the invention includes a U-shaped post 20 secured by one end 22 to the lower end 24 of clamp arm 4. The post 20 includes a clamping plate 26 which is welded to the lower end 22. Post 20 is attached to the clamp arm 4 by means of set screws 28 which pass through the flanges of post 20 and plate 26 as shown in Figures 2 and 3. Post 20 extends from its attached end 22 to a point intermediate the ends of arm 4 and may be tapered as shown or in the form of a standard structural channel.

A clamping plate 30 is secured to arm 4 adjacent to and spaced from the free end of post 20 by means of set

2

screws 32. A leaf spring 34 may be disposed on plate 30 by means of angle bracket-and-bolt means 35 with a portion 36 of the spring extending over the space between the free end of post 20 and plate 30. A lever 38, which may be in the form of an angle, is connected at its upper end with the spring 34 and extends therefrom over post 20 toward the lower end of clamp arm 4. Although I have shown lever 38 connected with clamp arm 4 by means of plate 30 and the spring 34 it will be noted that other suitable pivotal connecting means, such as a hinge, could be used in place of spring 34 if desired. However, a leaf spring connection is preferable since this eliminates excessive play and lost motion in the system.

A fulcrum 40, which I have shown in the form of an angle section resting on its end, is welded or otherwise rigidly mounted on the post 20 at its free end adjacent lever 38. The lever is held against the fulcrum by means of a bolt 42 and helical coil spring 44. The bolt 42 extends through enlarged openings in the lever and the fulcrum. The spring 44 is disposed around the bolt with its one end bearing against the head of the bolt and its other end bearing against a washer 46 positioned against the lever, as best shown in Figure 5. The distal end of the bolt 42 is anchored by means of a plate 48 disposed inside the fulcrum and a pin 50. This spring loaded bolt arrangement for holding the lever against the fulcrum also functions to prevent excessive play and lost motion in the system.

A limit switch 52 is mounted on the plate 26 of post 20 adjacent the lower end of the lever 38. The switch 52 is connected in an electrical circuit with a remotely located lamp (not shown). The limit switch and lamp may be so connected that the lamp lights when the limit switch is engaged by the lower end of lever 38.

In operation, when a load is applied to spring 14, the spring exerts pressure on the linkage 12 connecting the upper portions of clamp arms 4 and 4'. The pressure applied by spring 14 causes the upper ends of arms 4 and 4' to move away from each other and the lower ends of the arms to approach each other to clamp the head of the rail R. After the arms 4 and 4' are in rail-clamping position, a slight amount of deflection occurs in both arms caused by the continued pressure of spring 14. Post 20, which is attached by only one end to the lower portion of arm 4, does not deflect; thus there is relative movement between the free end of the post 20 and the clamp arm 4. This relative movement, which in itself is too small to be useful, is amplified by the lever arrangement of the invention. The relative movement of the arm 4, to which plate 30 and spring 34 are attached, and post 20 causes the upper or short arm portion of lever 38 to rotate about the fulcrum 40 producing an amplified movement of the free lower end or long arm portion of lever 38. The amplified motion of the lower end of lever 38 causes it to engage and actuate the limit switch 52 causing the lamp to light. Lighting of the lamp thus indicates that the clamping mechanism is set in rail-clamping position. It will be noted that the limit switch and lamp may be so connected that the lamp would be caused to light only when the clamping mechanism is not in rail-clamping position, if desired.

While one embodiment of my invention has been shown and described, it will be apparent that other adaptations and modifications may be made without departing from the scope of the following claims.

I claim:

1. In a rail-clamping mechanism, the combination with an elongated clamp arm adapted to engage a track rail, said arm extending substantially vertically and being pivoted adjacent its lower end, a post attached by one end to said arm adjacent the lower end of said arm and ex-

tending therefrom toward the upper end of the arm, a lever pivotally attached by one end to the upper end of said arm and extending therefrom over said post toward the lower end of the arm, switch means on said post adapted to be engaged and actuated by the lower end of said lever, and a fulcrum on said post adapted to effect tilting of said lever on deformation of said arm under rail-clamping force.

2. In a rail-clamping mechanism the combination as defined by claim 1 characterized by a leaf spring carried

4
by the upper end of said arm, and said one end of said lever being attached to said spring.
